UNITED STATES PATENT OFFICE.

ALBERT A. STRAUB, OF PITTSBURGH, PENNSYLVANIA, AND ERNEST B. PRIEBE, OF NEW YORK, N. Y.; SAID STRAUB ASSIGNOR TO SAID PRIEBE.

GAUGE.

1,402,187.

Specification of Letters Patent. Patented Jan. 3, 1922.

Application filed January 31, 1919. Serial No. 274,286.

To all whom it may concern:

Be it known that we, ALBERT A. STRAUB, a citizen of the United States, residing at Pittsburgh, in the county of Allegheny and State of Pennsylvania, and ERNEST B. PRIEBE, a citizen of the United States, residing at New York city, in the county of New York and State of New York, have invented new and useful Improvements in 10 Gauges, of which the following is a specification.

This invention relates to gauges for furnaces and steam boilers which are equipped with automatic stokers using forced draft.

The object of the invention is to provide a device for guiding firemen in the proper handling of such furnaces or steam boilers to the end that certain conditions may be maintained whereby the utmost efficiency, in 20 the operation of the particular furnace or boiler to which the device is applied, may be obtained.

These conditions are as follows:

1. To pass a definite quantity of air through the fuel bed in a certain time and at a certain pressure to burn the fuel properly and economically.

2. To supply the correct quantity of fuel to the furnace by means of the stoker mechanism.

3. Having given a certain size and type of boiler to secure the utmost efficiency of said boiler by supplying the proper quantity of coal, the proper quantity of air and the proper amount of pressure to burn said coal.

It is well known that to burn fuel properly and economically a definite quantity of air must be passed through the fuel bed of a furnace or boiler in a certain time. The

40 quantity of air passed through the fuel bed in furnaces or steam boilers which are equipped with automatic stokers is proportionate to the pressure of air under the fuel bed. It is therefore obvious that for proper

45 combustion of fuel with forced draft a definite relation exists between the quantity of fuel fed and the air pressure under the fuel bed. With automatic stokers, which supply a given quantity of fuel to the furnace per

50 ram stroke we can, by timing the frequency of occurrence of these strokes and by means of fixed relations, which exist, determine the air pressure necessary to properly burn the fuel, or vice versa, the pressure of air under

55 the fuel bed will indicate the frequency of

occurrence of ram strokes necessary for the proper combustion of the fuel supplied.

When the size and type of a boiler is known, its efficiency, when operated at different per cents of its rated horse power 60 capacity equipped with certain types and sizes of stokers, is also known. With a knowledge of these factors, the amount of coal required to be burned efficiently can be calculated and will remain practically constant for any one specified boiler rating for fuel of uniform character received at any one plant. Therefore, the boiler capacity desired will determine the amount of coal to be burned per unit of time which will in 70 turn determine the air pressure necessary to burn it properly. It is therefore evident that an indication of the pressure of air under the fuel bed can be used to determine simultaneously on adjacent scales the proper 75 amount of coal to be burned or rate of ram stroke to generate the corresponding boiler capacity that will be developed.

The invention consists in the combination and arrangement of parts set forth in the 80 following specification and particularly pointed out in the claims thereof.

Referring to the drawings:

Figure 1 represents a transverse section through the fuel bed of a steam boiler 85 equipped with an underfeed stoker, our improved gauge being illustrated in connection therewith.

Fig. 2 is a front elevation of the type of gauge shown in connection with Fig. 1. 90

Fig. 3 is a vertical section taken on the line 3—3 of Fig. 2.

Fig. 4 is a horizontal section taken on the line 4—4 of Fig. 2.

Fig. 5 is a front elevation of a modified 95 construction in which our invention is shown in connection with a bellows type of air pressure gauge.

Fig. 6 is a section on the line 6—6 of Fig. 5. 100

Like numerals refer to like parts throughout the several views of the drawings.

In the drawings, 10 represents a furnace, the same being equipped with an automatic stoker mechanism 11 of well-known construction. 12 represents the wind box located below the grate mechanism 13. An air inlet pipe 14, in which is a damper 15, connects with the wind box 12 and is adapted to furnish air thereto. 110

The gauge embodying our invention is mounted adjacent to the stoker mechanism, as illustrated in Fig. 1, and consists of a gauge panel 16 upon which is mounted a transparent U shaped tube 17 adapted to contain a liquid, said U shaped tube being connected to the wind box 12 of the boiler by means of an inlet pipe 18. The tube 17 is fastened to the panel 16 by means of 5 brackets 19 and 20. A gauge scale panel 21 is mounted between the arms 22 and 23 of the U shaped tube 17, said gauge scale panel being constructed in two parts 24 and 25, the edges of said panel being adapted to 10 tightly fit the U shaped tube and adapted to be adjusted vertically thereupon. A series of graduations 26 representing the pressure within the wind box is placed upon the gauge scale panel 21 adjacent to 15 the arm 22 of the U shaped tube.

As the pressure rises within the wind box of the boiler, said pressure is exerted upon the liquid in the arm 22 of the U shaped tube and causes said liquid to be depressed a certain distance below the level of zero, indicated by the graduations 26, with a consequent equal rise of the level of said liquid in the column 23. The level of the liquid in the arm 22 as it registers with the graduations 26 will indicate the true pressure of 20 the air in the wind box 12.

Mounted upon the gauge scale panel 21 adjacent to the arm 23 of the U shaped tube and parallel therewith is a rod 27, said rod being supported by brackets 28 fast to the gauge scale panel. A plurality of indicators 29, each provided with oppositely disposed pointers, are adjustably mounted upon the rod 27 and upon each indicator is placed a 25 figure or figures representing a certain period of time which is indicated in minutes or seconds or both. This series of indicators constitutes a scale representing combustion rate which is the length of time it takes for 30 the crank or acting mechanism of the plunger of the stoker to make one complete revolution in order to feed the proper amount of coal into the furnace to bring about the necessary relations between the amount of 35 fuel fed and quantity of air which is necessary for a proper combustion. These indicators are placed so as to register with the different levels to which the liquid is forced in the arm 23 of the U shaped tube 17 by the 40 different pressures of air beneath the grate mechanism. As has been previously stated for a given size and type of steam boiler and a uniform fuel the pressure within the wind box will indicate a definite coal burning rate for proper conditions of combustion. Therefore, as the level of liquid rises 45 in the arm 23 and registers with the indicators 29 representing the combustion rate, it will indicate to the fireman that the stoker 50

mechanism must be regulated to make one 65 revolution in the length of time as designated upon the indicator which may be for example in one minute and fifty seconds as indicated by numerals upon the lower of the indicators 29 illustrated in Figure 2. 70

Another rod 30 which is similar to the rod 27 and parallel thereto is mounted in the brackets 28 and has adjustably mounted thereon a plurality of indicators 31, each provided with oppositely disposed pointers, 75 each indicator having thereon a number representing a certain per cent. of the rated horse power capacity of the boiler. This series of indicators also constitutes a scale and represents the per cent. boiler rating or 80 in other words, the per cent. of the rated horse power capacity of the boiler. As the level of the liquid rises in the arm 23 and registers with the indicators 29 and 31 it will simultaneously indicate the combustion 85 rate or speed at which it is necessary to operate the stoker mechanism and also give the per cent. of the rated horse power capacity at which the boiler is running.

The operation of a steam boiler which has 90 our improved gauge applied thereto is as follows: Assuming that the fireman desires to operate the boiler to deliver a certain percentage of its rated horse power capacity, he first adjusts the air pressure in the wind 95 box until the level of the liquid rises in the arm 23 of the U shaped tube to align with one of the indicators 31 upon which is indicated the desired rating, he next adjusts the ram stroke rate to that designated 100 by the indicator 29, which is on the same level with the boiler rating indicator, in consequence of which the proper amount of fuel will be fed to the boiler, thereby establishing the proper furnace conditions. 105 On the other hand, if the fireman is feeding fuel at a certain rate and desires to determine the necessary air pressure to burn this fuel, he adjusts the air pressure until the record of this pressure indicates this fuel 110 burning rate. In a similar manner the fuel feeding rate can be determined from the air pressure intensity.

The adjustable indicators are set for each 115 individual type of boiler from what are known as the characteristic operating curves for said stoker, said information being given by the makers of said stoker.

In Figs. 5 and 6 another form of our invention is illustrated applied to a bellows 120 type of air pressure gauge. In this type of gauge the pressure within the wind box is indicated by the pointer 34 which registers with a series of graduations 35 upon a panel 36. A slot 37 is formed in the panel 125 36, said slot describing the arc of a circle and being parallel to the series of graduations 35. Indicators 38 are adapted to slide

in the slot and align with the graduations 35, said indicators 38 being held at any desired location by means of thumb screws 39. This series of indicators constitutes a 5 scale and represents the combustion rate.

Another slot 40 is also formed in the panel 36 and is concentric with the slot 37. Indicators 41 are adapted to slide in the slot 40 and are held therein by thumb 10 screws 42, said indicators having thereon a number representing a certain per cent. This series of indicators also constitutes a 15 scale and represents the per cent. boiler rating. Each of these sets of indicators are arranged radially with the graduations 35 and also with the pointer 34.

The information obtained from the readings of this gauge is exactly the same as the information contained on the form of gauge 20 illustrated in Figs. 1 to 4 inclusive.

Having thus specifically described our invention what we claim and desire by Letters Patent to secure is:

1. In a furnace, an automatic stoker having means to regulate rate of fuel feed to furnace, a regulable means to supply air under pressure beneath the fuel bed in the furnace, and a movable gauging element (for example, liquid or finger) operated by the 30 air pressure beneath the fuel bed and so taking a position corresponding to the total air-supply rate, which varies approximately in proportion to such pressure, and a set of index graduations alongside the guaging 35 element indicating the proper rates of fuel

feed corresponding to different rates of air supply, whereby the operative may readily bring the air supply and fuel feed into efficient correspondence.

2. A furnace and elements as in claim 1 40 and wherein is combined a second set of index graduations alongside the gauging element indicating the power or total output of the furnace, or a boiler operated thereby, under any given conditions of air supply 45 and corresponding fuel feed, for example, in terms of percentage of the full rated power, whereby the operative may readily adjust the air and fuel to give any desired power up to the full rated power. 50

3. A gauge for a boiler furnace or other furnace having automatic fuel feed and regulable air supply, the said gauge having a movable gauging element which assumes a position corresponding to the existing rate 55 of air supply, and a set of graduations indicating the most efficient fuel feed rates for the differing air supply rates.

4. A gauge as in claim 3 and wherein is provided a second set of graduations indicating the total power of the furnace under given conditions of air supply with corresponding fuel feed, whereby the operative may readily adjust the air and fuel to give any desired power up to the full rating. 60 65

In testimony whereof we have hereunto set our hands.

ALBERT A. STRAUB.
ERNEST B. PRIEBE.
